[57] CLAIM

The ornamental design for a shelf-mounted rack, as shown and described.

DESCRIPTION

FIG. 1 is a top perspective view of a shelf-mounted rack showing my new design;

FIG. 2 is a bottom perspective view thereof;

FIG. 3 is a right side elevational view thereof, the left side being a mirror image; and

FIG. 4 is a vertical cross-sectional view thereof, taken along line 4—4 of FIG. 2. The partial broken-line showing of a shelf in FIGS. 3 and 4 is for illustrative purposes only and forms no part of the claimed design.
